US00D336889S

United States Patent [19]

Boyer

[11] Patent Number: Des. 336,889

[45] Date of Patent: ** Jun. 29, 1993

[54] PRESSURE TRANSDUCER

[75] Inventor: Gregory S. Boyer, Freeport, Ill.

[73] Assignee: Honeywell Inc., Minneapolis, Minn.

[**] Term: 14 Years

[21] Appl. No.: 800,381

[22] Filed: Nov. 26, 1991

[52] U.S. Cl. D13/101
